UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

ADDRESSING-MACHINE.

1,280,191.

Specification of Letters Patent.

Patented Oct. 1, 1918.

Application filed March 2, 1916. Serial No. 81,600.

To all whom it may concern:

Be it known that I, JOSEPH S. DUNCAN, a citizen of the United States, residing at Chicago, in the county of Cook and State of Illinois, have invented certain new and useful Improvements in Addressing-Machines, of which the following is a specification.

This invention relates in general to printing machines and more particularly to a machine for printing addresses and matter of a like nature from printing devices bearing such matter and fed successively to printing position on the machine.

It is an object of my invention to provide a printing machine in which the platen pressure will be uniform throughout the printing operation and which will prevent any inequalities in the type surface of the printing devices from affecting the impressions obtained therefrom.

It is a further object of my invention to provide a machine in which the printing is accomplished by a rolling pressure exerted on a printing device in a direction lengthwise to the lines of type thereon.

A further object of my invention is the provision in a machine for printing addresses and the like of a bodily movable roller platen adapted to exert pressure on a printing device between which and the platen an inking ribbon and the impression-receiving material is disposed.

A still further object of my invention is the provision of a hand-operable machine for printing addresses and the like from printing devices, automatically fed to printing position, by pressure exerted by a bodily movable roller platen moving in the direction of the lines of type on the printing devices.

Further objects and advantages of my invention will be apparent as it is better understood by reference to the following specification when read in connection with the accompanying drawing, illustrating the preferred embodiment thereof, in which—

Figure 1 is a side elevation of the printing machine according to my invention;

Fig. 2 is an end elevation of the structure illustrated in Fig. 1;

Fig. 3 is a plan view of the structure illustrated in Figs. 1 and 2;

Fig. 4 is an enlarged end elevation of the platen structure;

Fig. 5 is an enlarged side elevation of the

platen structure illustrating the operative position of the platen, and

Fig. 6 is a similar view illustrating the inoperative position of the platen.

Referring to the drawing, 1 indicates a base preferably of cast metal and hollow to support the various parts of the mechanism presently to be described. A magazine 2 is disposed at the rearward end of the base 1 and is adapted to contain a plurality of printing devices 2'. Slidably mounted on the base 1 and extending longitudinally thereof are a pair of members 3, each provided with a plurality of dogs 4 pivotally connected thereto at 5 and biased upwardly by springs 6. The members 3 are connected by transverse members 7, thus forming a rigid frame which may be reciprocated by means of the link 8 pivotally connected at 9 to one of the transverse members 7 of the frame and at 10 to an arm 11 preferably formed integral with an operating handle 12 pivotally mounted at 13 on the base 1.

When the handle 12 is actuated and the members 3 are thereby reciprocated, the dogs 4 pass beneath the printing devices 2' in the magazine 2 and advance them successively longitudinally of the base 1 to a position above the printing bed 14 and beneath the ribbon 15 mounted on spools 16 and adapted to be advanced transversely of the base 1 in either direction by suitable mechanism which forms no part of my present invention and is accordingly not illustrated. An arm 17 is pivotally mounted at 18 at the rearward end of the base 1 and is normally held in the position indicated in Fig. 2 by a spring 18 secured thereto and to a bracket 19 on the base 1. At its forward end the arm 17 is provided with a bifurcated member 20 disposed to receive the printing devices after they are advanced beyond the bed 14. As the printing devices accumulate on the member 20 the spring 18 allows the member 20 to descend. A plate 21, secured to the base 1 forwardly of the printing bed 14, serves to support the impression-receiving material and a guide 22 secured to rods 23 adjustably mounted in brackets 24 on the base 1 provides a guide against which the edge of the impression-receiving material may rest to insure proper alignment of the impression.

Projecting upwardly and forwardly from the base 1 is a rigid platen arm 25 provided

at its forward end with a track 26 to slidably support the platen structure. This structure comprises a frame or carriage 27 provided with rollers 28 adapted to ride on the track 26. A link 29, pivotally secured to an arm 30 of the frame 27 and to a lug 31 depending from the operating arm 12, provides an operating connection whereby the frame 27 is reciprocated when the operating arm 12 is actuated to perform the printing operation.

Pivottally mounted on a shaft 32 extending transversely of the frame 27 are a pair of links 33 connected by a transverse member 34. A spring 35 is disposed between the transverse member 34 and an arm 36 rigidly connected to the frame 27. A shaft 37 connects the ends of the links 33 and the yoke 38 is pivotally mounted thereon. A platen roller 39 is pivotally mounted on a shaft 40 extending transversely of the yoke 38 and an anti-friction roller 41 is pivotally mounted on the shaft 37 and engages the face of the platen roller 39. An arm 42 pivotally connected to a boss 40' on the yoke 38 by a pivot screw 42' (Fig. 4) and having its end in engagement with the shaft 37 is connected by a spring 43 to a lug 44 on the frame 27. The spring 43 normally tends to draw the arm 42 and consequently the yoke 38 to the position indicated in Fig. 6 in which the platen roller 39 is disposed in inoperative position. A lever 45 is secured to the arm 42 and is normally held in the position indicated in Fig. 6 by a spring 46 secured at one end to an extension 45' of the lever 45 and at the other to a pin 46' on the yoke 38. The opposite end of the lever 45 is adapted to coöperate with the roller 47 mounted on the rigid platen arm 25 (Fig. 1), the spring 46 allowing the lever 45 to rotate as the frame 27 moves in the direction of the arrow on Fig. 6. An arm 48, secured to the yoke 38, is adapted to engage an abutment 49 on a latch 50 pivotally mounted at 51 on the frame 27.

The latch 50 is normally held by a spring 52 secured at one end thereto and at the opposite end to a pin 53 supported on the frame 27 in the position indicated in Fig. 5. The latch 50 is provided with a cam portion 54 at its end which is adapted to coöperate with an abutment 55 at the end of the track 26 and, as will be apparent, when the latch 55 is actuated by engagement with the abutment 55 the lever 48 will be released and the spring 43 will move the yoke 38 to the position indicated in Fig. 6. Upon the return movement of the frame 27 in the direction indicated by the arrow in Fig. 6 the lever 45 will pass beneath the roller 47 and when the frame 27 is again moved in the direction of the arrow on Fig. 5 the lever 45, through its connection with the arm 42, will move the yoke 38 to the position indicated in Fig. 5.

Upon continued movement the anti-friction roller 41 will engage a track 56, thus causing the platen roller 39 to exert the desirable pressure to accomplish the printing operation. A bumper 57 of felt or other suitable material is mounted on the frame 27 to prevent injury of the platen surface when the platen roller is moved to its inoperative position.

The operation of the machine will be more clearly understood from the following brief description. A supply of printing devices 2' being disposed in the magazine 2, the operating arm 12 is actuated to feed the printing devices forwardly to position above the bed 14 and in the path of the platen roller 39. As the arm 12 is actuated the frame 27 will be reciprocated above the printing bed and the mechanism is so timed that a printing device 2' will be disposed on the printing bed 14 and beneath the ribbon 15 when the frame 27 is in the position indicated in Fig. 6. Upon movement of the frame 27 to the left, viewing Fig. 6, the lever 45 will engage the roller 47 and move the yoke 38 to the position indicated in Fig. 5 and upon continued movement the anti-friction roller 41 will ride onto the track 56 to move the yoke 38 and the platen roller 39 into engagement with the impression-receiving material, which has previously been disposed by the operator above the ribbon 15 and in the path of the platen roller 39. It will be noted that the movement of the platen roller 39 is longitudinal with respect to the printing device and the lines of type thereon and hence the platen roller 39 contacts with relatively few type characters at any position in its travel. Consequently a very small amount of power is necessary to operate the machine and inequalities in the surface of the printing device do not affect the impression to the extent that the impression would be affected if the platen roller was moved in a direction transverse to the lines of type on the printing device. When the frame 27 reaches the limit of its travel in the direction of the arrow on Fig. 5 the cam portion 54 of the latch 50 engages the abutment 55 to release the lever 48 and the yoke 38 is immediately moved to the position indicated in Fig. 6 by the spring 43 in which position it remains while the frame 27 is returned to the position indicated in Fig. 6. The cycle of operations is then repeated, a printing device being fed to printing position above the bed 14 and an impression being taken therefrom at each movement of the frame 27 in the direction of the arrow on Fig. 5.

It will be readily understood from the foregoing that I have perfected a printing machine adapted to accomplish desired results in a novel manner and by means of novel mechanism. It will be appreciated,

moreover, that various changes may be made in the form, construction and arrangement of the parts without departing from the spirit and scope of the invention or sacrificing any of its material advantages, the form hereinbefore described being merely a preferred embodiment thereof.

I claim:

1. In a printing machine, the combination 10 of a bed, a rigid support above said bed, a platen carriage mounted to reciprocate on said support, a rotatable platen mounted to swing on said carriage, means for actuating said carriage to move said platen over said bed, a magazine adapted to contain a plurality of printing devices, and means connected to said carriage-actuating means for advancing printing devices from said magazine to said bed.
2. In a printing machine, the combination 20 of a bed, a rigid support above said bed, a platen carriage movably mounted on said support, a rotatable platen supported by said carriage, a roller mounted in said carriage and engaging said platen, a track on said support adapted to be engaged by said roller, and means for actuating said carriage to move said platen over said bed.
3. In a printing machine, the combination 30 of a bed, a rigid support above said bed, a platen carriage movably mounted to reciprocate on said support, a rotatable platen supported by said carriage, means for moving said platen to operative and inoperative 35 positions relative to said bed, means for actuating said carriage to move said platen over said bed, a magazine adapted to contain a plurality of printing devices, and means connected to said carriage-actuating means 40 for advancing printing devices from said magazine to said bed.
4. In a printing machine, the combination 45 of a bed, a rigid support above said bed, a platen carriage movably mounted on said support, a rotatable platen supported by said carriage, a roller mounted in said carriage and engaging said platen, a track on said support adapted to be engaged by said roller, means for moving said platen to operative 50 and inoperative positions relative to said bed, and means for actuating said carriage to move said platen over said bed.
5. In a printing machine, the combination 55 of a bed, a rigid support above said bed, a platen carriage movably mounted on said support, a rotatable platen mounted to swing on said carriage, resilient means normally tending to swing said platen to inoperative position relative to said bed, means 60 for retaining said platen in operative position, and means for actuating said carriage to move said platen over said bed.
6. In a printing machine, the combination 65 of a bed, a rigid support above said bed, a platen carriage movably mounted on said

support, a rotatable platen mounted to swing on said carriage, resilient means normally tending to swing said platen to inoperative position relative to said bed, means for releasably retaining said platen in operative 70 position, means for reciprocating said carriage to move said platen over said bed, and means operable when the carriage approaches the limit of its movement in one direction to release said retaining means. 75

7. In a printing machine, the combination 80 of a bed, a rigid support above said bed, a platen carriage movably mounted on said support, a rotatable platen mounted to swing on said carriage, resilient means normally tending to swing said platen to inoperative 85 position relative to said bed, means for releasably retaining said platen in operative position, means for reciprocating said carriage to move said platen over said bed, means operable when the carriage approaches the limit of its movement in one direction to release said retaining means, and means for subsequently moving said platen against the action of said resilient 90 means to operative position.

8. In a printing machine, the combination 95 of a bed, a rigid support above said bed, a platen carriage movably mounted on said support, a rotatable platen supported by 100 said carriage, a roller mounted in said carriage and engaging said platen, a track on said support adapted to be engaged by said roller, a spring normally tending to move said platen to inoperative position relative to said bed, means for retaining said platen in operative position, and means for actuating said carriage to move said platen over said bed.

9. In a printing machine, the combination 105 of a bed, a rigid support above said bed, a platen carriage movably mounted on said support, a rotatable platen supported by said carriage, a roller mounted in said carriage and engaging said platen, a track on said 110 support adapted to be engaged by said roller, a spring normally tending to move said platen to inoperative position, means for retaining said platen in operative position, means for reciprocating said carriage to 115 move said platen over said bed, and means operable when the carriage approaches the limit of its movement in one direction to release said retaining means.

10. In a printing machine, the combination 120 of a bed, a rigid support above said bed, a platen carriage movably mounted on said support, a rotatable platen supported by said carriage, a roller mounted in said carriage and engaging said platen, a track on said 125 support adapted to be engaged by said roller, a spring normally tending to move said platen to inoperative position relative to said bed, means for releasably retaining said platen in operative position, means for re- 130

ciprocating said carriage to move said platen over said bed, means operable when said carriage approaches the limit of its movement in one direction to release said retaining means, and means for subsequently moving said platen against said spring to operative position.

11. In a printing machine, the combination of a bed, a rigid support above said bed, a platen carriage movably mounted on said support, a yoke pivotally connected to said carriage, a rotatable platen supported by said yoke, resilient means normally tending to move said yoke and platen to inoperative position relative to said bed, a latch for releasably retaining said yoke and platen in operative position, means for reciprocating said carriage to move said platen over said bed, an abutment on said support for releasing said latch when said carriage approaches the limit of its movement in one direction, an arm connected to said yoke, and an abutment on said support adapted to be engaged by said arm whereby said yoke and platen are subsequently returned to operative position.

12. In a printing machine, the combination of a bed, a rigid support above said bed, a platen carriage movably mounted on said support, a yoke pivotally connected to said carriage, a rotatable platen supported by said yoke, a roller supported by said carriage in engagement with said platen, a track on said support adapted to be engaged by said roller when said platen is in operative position relative to said bed, a spring normally tending to move said yoke and platen to inoperative position, a latch for releasably retaining said yoke and platen in operative position, means for reciprocating said carriage to move said platen over said bed, an abutment on said support for releasing said latch when said carriage approaches the limit of its movement in one direction, an arm connected to said yoke, and an abutment on said support adapted to be engaged by said arm, whereby said yoke and platen are subsequently returned to operative position.

13. In a printing machine, the combination of a bed, a magazine adapted to contain a plurality of printing devices, means for intermittently advancing printing devices from said magazine along said bed, a rigid support above said bed, a carriage mounted on said support, a roller platen mounted to swing on said carriage, means for moving said carriage in a direction substantially normal to the direction of movement of said printing devices to obtain impressions therefrom and means for swinging said platen to operative and inoperative positions relative to said bed.

14. In a printing machine, the combination of a bed, a magazine adapted to contain

a plurality of printing devices, means for intermittently advancing printing devices from said magazine along said bed, a rigid support above said bed, a carriage depending from said support, a roller platen mounted to swing on said carriage, an inking ribbon disposed between said platen and the printing devices on said bed, means for moving said carriage in a direction substantially normal to the direction of movement of said printing devices to obtain impressions therefrom and means for swinging said platen to operative and inoperative positions relative to said bed.

15. In a printing machine, the combination of a bed, a magazine adapted to contain a plurality of printing devices, means for intermittently advancing printing devices from said magazine along said bed, a rigid support, a platen carriage movably mounted on said support above said bed, a rotatable platen mounted to swing on said carriage toward and from printing position, an inking ribbon disposed between said platen and the printing devices on said bed, and means for reciprocating said carriage to move said platen over said bed in a direction substantially normal to the direction of movement of said printing devices.

16. In a printing machine, the combination of a bed, a magazine adapted to contain a plurality of printing devices, means for intermittently advancing printing devices from said magazine along said bed, a rigid support, a platen carriage movably mounted on said support above said bed, a rotatable platen mounted to swing on said carriage toward and from printing position, means for reciprocating said carriage to move said platen over said bed in a direction substantially normal to the direction of movement of said printing devices, and a connection between said carriage reciprocating means and printing device advancing means.

17. In a printing machine, the combination of a bed, a magazine adapted to contain a plurality of printing devices, each bearing one or more lines of type extending lengthwise thereof, means for intermittently advancing printing devices sidewise from said magazine along said bed, a platen carriage, a roller platen supported thereon, and means for reciprocating said carriage over said bed in directions substantially normal to the direction of movement of said printing devices, and means controlled by the movement of said carriage for moving said platen to operative and inoperative positions relative to said bed.

18. In a printing machine, the combination of a bed, a magazine adapted to contain a plurality of printing devices, each bearing one or more lines of type extending lengthwise thereof, means for intermittently advancing printing devices sidewise from said

magazine along said bed, a rigid support, a platen carriage mounted to reciprocate above said bed on said support, a rotatable platen mounted to swing on said carriage, means for actuating said carriage to move said platen in a direction substantially normal to the direction of movement of said printing devices, and means controlled by the movement of said carriage to swing said 10 platen to operative and inoperative positions relative to said bed.

19. In a printing machine, the combination of a bed, a magazine adapted to contain a plurality of printing devices, each bearing 15 one or more lines of type extending lengthwise thereof, means for intermittently advancing printing devices from said magazine along said bed, a rigid support, a platen carriage mounted to reciprocate above said 20 bed on said support, a rotatable platen supported in swinging relation to said carriage, means for swinging said platen into and out of operative position relative to said bed, and means for actuating said carriage to move 25 said platen in a direction substantially nor-

mal to the direction of movement of said printing devices.

20. In a printing machine, the combination of a bed, a magazine adapted to contain a plurality of printing devices, each bearing 30 one or more lines of type extending lengthwise thereof, means for intermittently advancing printing devices from said magazine along said bed, a rigid support, a platen carriage mounted to reciprocate above said 35 bed on said support, a rotatable platen supported in swinging relation to said carriage, means for swinging said platen into and out of operative position relative to said bed, means for actuating said carriage to 40 move said platen in a direction substantially normal to the direction of movement of said printing devices, and a connection between said carriage-actuating means and printing-device advancing means.

JOSEPH S. DUNCAN.
